UNITED STATES PATENT OFFICE.

AUGUST JAEGER AND ALEXANDER JAEGER, OF PHILADELPHIA, PENNSYLVANIA.

VENDING-MACHINE.

1,098,264

Specification of Letters Patent.

Patented May 26, 1914.

Application filed October 4, 1911. Serial No. 652,684.

To all whom it may concern:

Be it known that we, AUGUST JAEGER and ALEXANDER JAEGER, citizens of the United States, and residents of Philadelphia, Pennsylvania, have invented certain Improvements in Vending-Machines, of which the following is a specification.

Our invention relates to check-controlled vending machines; and the object of our invention is to provide a structure designed more particularly for the vending of edibles, being available for use in the so-called "automats" or automatic lunch rooms where the articles of food are vended from cabinets having mechanism which may be operated to permit opening of a door of such cabinet upon the insertion of a coin or other check.

A further feature of our invention is to provide means for maintaining such edibles hot or cold, as the case may be.

These and other features of our invention are more fully described hereinafter, reference being had to the accompanying drawings, in which:

Figure 1, is a front elevation of one section of a vending cabinet arranged and operating in accordance with our invention; Fig. 2, is a sectional plan view on the line *a—a*, Fig. 1; Fig. 3, is a sectional plan view on the line *b—b*, Fig. 1; Fig. 4, is a rear elevation of the structure shown in Fig. 1, and Fig. 5, is a cross sectional view on the line *c—c*, Fig. 1, showing a plurality of compartments with certain of the operating parts in different positions.

The wall of the cabinet may be made up of metal plates 1, carried by channel members 2 forming a light frame, or otherwise constructed as may be desired; said front having apertures 3, closed by doors 4, which may be hinged at 5. The doors are preferably glazed, as indicated at 6, and carry an internally disposed shelf 7, upon which a plate 8 may be placed; such plate serving to carry the edible to be vended. (Not shown). The doors may be provided with handles, and in the present instance they comprise a hollow portion 9, terminating in a knob 10, upon which may be displayed the name of the edible in the particular compartment. The hollow portion of the handle is for a special purpose, hereinafter described.

At a suitable point, above the handles for instance, slots 11 are formed in the front

wall of the structure for the insertion of a coin, check or other element, as may be desired, and these slots may be corrugated as shown. Provision is made for closing these slots from the inside of the casing, by means of a plate 12 suitably mounted, which plate is arranged to be moved over a slot; its position being controlled by the edible carrier or receptacle 8 on the door shelf 7. These shelves are provided with shoulders or stops 13 against which the plate abuts on one side, while another portion of the plate engages a pivoted arm 14 which controls the open position of the slot closing plate 12. The plate is adapted to slide in suitable ways 15, and a lever 16 pivoted to the casing at 17 is operatively connected therewith. This lever is connected to the pivoted arm 14 by means of a link 18, and a spring 19, suitably anchored, is connected to said lever and moves the same when the edible carrier is lifted and releases the arm 14. In addition, the slot closing plate is combined with means to indicate to the person whose duty it is to keep the compartments full, the fact that a compartment is empty. For this purpose, I provide a rocking rod 20 journaled in suitable supports, and having a disk 21 at one end, with a pin 22 in operative engagement with the slot closing plate 12. At the opposite end of the rod 20 a signal 23 may be mounted, which signal will be disposed in one position when the compartment is filled and in another position when the compartment is empty. When the edible carrier is removed from the shelf, the arm 14 and the lever 16 connected thereto by the link 18 are released and under the action of the spring 19, said lever is moved and with it the plate 12 closing the coin slot; the movement of the latter rocking the shaft or rod 20 to show the signal indicating that the compartment is empty.

To retain the door in the shut position, a catch lever 25 may be employed, pivoted at 26 and having a shoulder 27 engaging a suitable projecting portion 28 of the door, which projection forms the end wall of the hollow portion 9 of the handle; the end of such catch projecting into the hollow portion. The opposite end of the catch lever may be flattened as indicated at 29, and lies in the path of a coin *x* delivered from a coin chute, shown at 30, in communication with the slot 11. Below the catch lever is a spring finger 31, suitably supported and sufficiently

stiff to support the end of the said lever 29 and hold the coin in the chute until the door is fully opened, as shown in Figs. 5 and 6. The weight of the coin is sufficient 5 to move the lever on its pivot and free the shoulder from its engagement with the projecting portion 28 of the door, and the latter may then be opened. In opening, the projecting portion 28 of the door engages 10 a cam 32 at the end of the catch lever and continued opening movement of the door rocks the catch lever on its pivot against the tension of the spring finger 31, permitting release of the coin which drops into the 15 main conduit or coin chute 30^a leading to the money box. (Not shown). The forward end of the catch lever is beveled or provided with a cam surface 33 so that as the door closes the projecting portion 28 of the 20 latter will engage and lift the same sufficiently to permit such closing action, and when the door is closed the forward end of the catch lever will drop into engagement with the portion 28 of the door and hold the 25 same locked; the forward end of said lever being the heavier.

To close the door automatically, we provide a chain 35 connected at one end to the door, passing over a small pulley 36 connected to the rear face of the wall 1, and having its opposite end attached to a spring 37, also connected to the rear face of the wall 1. Upon releasing the door, the spring will return it with sufficient force to effect latching of the same.

In connection with the vending of the edibles, it may be desirable to maintain the same at various temperatures, hot or cold, as the case may be, and for this purpose we 40 provide insulating casings 40, which may be of sufficient height to embrace a plurality of the shelves carrying the edibles. These casings may be filled with hot water, or a suitable connection may be made to circulate 45 steam within the same, or a simple form of burner, Bunsen or the like, may be employed to heat the water, if it be desired to maintain the edibles hot, or the casings may be arranged to contain ice or cold water in case 50 the edibles to be vended require a cool condition; ice cream or cold drinks for instance.

The insulating casings are preferably horse-shoe shaped, as indicated in the sectional plan views, and they are preferably 55 mounted upon wheels 41, adapted to suitable rails 42, whereby they can be readily moved for the replenishing of the different shelves at any time. As shown in the drawings, the insulating structures are designed 60 to fit between the respective door operating mechanisms and to bear such relation thereto as not to interfere with the working of the

same, nor with the slot closing plate. The insulating casings will be provided with top openings for the placing of water, ice, &c., 65 such openings being closed by cover plates 43.

Although we have shown but one compartment in Figs. 1 to 4 of the drawings, it will be understood that a plurality of the same, arranged side by side and above and below 70 each other and each having the same parts and operating in the same manner, will be employed, and in Fig. 5, we have shown a superposed pair.

We claim:

1. In a check-controlled mechanism, the combination of an apertured casing, a door for closing such aperture, a coin chute, a pivotally mounted lever having a weighted catch for the door and a flat portion underlying the coin chute, a spring underlying the flat portion of the lever, the weight of the coin delivered by said chute depressing the flat end of the lever and effecting partial release of said catch whereby the door may be 80 opened, and a plurality of cams carried by said lever adjacent the catch portion for engagement by the door in the opening and closing of the same; such engagement effecting movements of the flat end of the 85 lever into contact with the spring and the coin being released upon that depression of the spring attendant upon the full opening of the door.

2. In check-controlled mechanism, the combination of an apertured casing, a door for closing such aperture, a coin chute, a pivotally mounted lever having a weighted catch for the door at one end and a flat portion underlying the coin chute at the opposite end, a spring beneath the flat portion of the lever, the weight of a coin delivered by said chute depressing the flat portion of the lever to an extent sufficient to effect partial release of said catch whereby 100 the door may be opened, and a plurality of inclined faces at right angles to each other carried by said lever adjacent its catch portion and forming cams, one of said cams being engaged by the door in opening and the other cam being engaged by the door in closing the same; such engagement effecting movements of the lever into contact with the spring and the coin being released upon that depression of the spring attendant upon the 110 full opening of the door.

In testimony whereof, we have signed our names to this specification, in the presence of two subscribing witnesses:

AUGUST JAEGER.

ALEXANDER JAEGER.
